GRINDING MACHINE

Charles H. Amidon, Worcester, Mass., assignor to
 Norton Company, Worcester, Mass., a corpora-
 tion of Massachusetts

Application March 30, 1936, Serial No. 71,543

10 Claims. (Cl. 51—95)

This invention relates to grinding machines, and more particularly to a hydraulically driven tool and cutter grinding machine.

One object of this invention is to provide a hydraulically operated tool and cutter grinding machine with an interlocked driving mechanism between the fluid pressure reciprocating mechanism and the manual traversing mechanism. Another object of this invention is to provide a fluid pressure reciprocating mechanism for the work support which permits one complete reciprocation of the table and then stops the table in a predetermined position at the end of its stroke. Other objects will be in part obvious or 15 in part pointed out hereinafter.

This invention accordingly consists in the features of construction, combinations of elements, and arrangements of parts, as will be exemplified in the structure to be hereinafter described, and 20 the scope of the application of which will be indicated in the following claims.

In the accompanying drawings in which is shown one of various possible embodiments of the mechanical features of this invention,

25 Fig. 1 is a front elevation of the improved grinding machine;

Fig. 2 is a fragmentary right-hand end elevation of the machine as shown in Fig. 1, having parts broken away and shown in section to more 30 clearly show the operation and construction;

Fig. 3 is a cross sectional view, taken approximately on the line 3—3 of Fig. 1;

Fig. 4 is a diagrammatic view, showing the fluid pressure system together with the interlock between the fluid pressure and the manual traverse mechanism;

Fig. 5 is a fragmentary front elevation, having parts broken away to more clearly show the table controlling mechanism;

40 Fig. 6 is a fragmentary sectional view, taken approximately on the line 6—6 of Fig. 1, showing the control valve and its operating mechanism;

Fig. 7 is a fragmentary vertical section, taken approximately on the line 7—7 of Fig. 2, showing the slide construction together with the elevating mechanism for the grinding wheel unit; and

Fig. 8 is a fragmentary sectional view, taken approximately on the line 8—8 of Fig. 1, showing the multiple speed device for manually traversing the table.

A grinding machine embodying this invention has been illustrated in the drawings, which comprises a base 10 which supports a vertically extending column 11. The column 11 is provided

with a cylindrical bore 12 which serves as a support for a cylindrically shaped post 13. The upper end of the post 13 is provided with a grinding wheel support 14 which may be angularly positioned in the post 13 and locked by means 5 of the bolts. The wheel support 14 rotatably supports a grinding wheel spindle 15. The grinding wheel spindle 15 is provided with a pair of grinding wheels 16 and 17 mounted at opposite ends thereof. The grinding wheels 16 and 10 17 are driven by an electric motor 18 mounted on the top of the wheel supporting unit 14. The motor 18 is provided with a pulley 19 which drives through belt 20 to a pulley 21 formed on the end of the wheel spindle 15. 15

The post 13 is arranged to be adjusted vertically so that the position of the grinding wheel spindle 15 and grinding wheel 16 may be adjusted in a vertical plane relative to the base 10. This is preferably accomplished by means of a 20 rotatable screw 24 which is rotatably supported in a bearing 25 in a portion of the base 10. The screw 24 passes through a nut 26 which is fixedly mounted in the lower end of the column 13. By rotating the screw 24, the nut 26 together with 25 the column 13 and the grinding wheels 16 and 17 may be raised or lowered, as desired. In order to facilitate vertical adjustment of the wheel unit, a manually operable hand wheel 30 is mounted on the outer end of a shaft 31, the inner end of which carries a bevel gear 32 which meshes with a bevel gear 33 keyed on the lower 30 end of the feed screw 24. By rotating the hand wheel 30, the screw 24 may be rotated to vertically adjust the positions of the grinding wheels 35 16 and 17. A graduated collar 34 is associated with the hand wheel 30 so that the extent of adjustment may be readily determined. In the preferred construction, it may be desirable to operate the vertical adjustment of the wheel from 40 either end of the machine base. As illustrated in the drawings, the shaft 31 is preferably supported in a quill or sleeve 35 which is supported in a cylindrical aperture 36 in the base 10. The casing surrounding the cylindrical bore 36 is 45 slotted at its lower edge and arranged to bind or clamp the quill 35 in place by means of a clamping screw 37. A similar bore 38 is provided at the opposite end of the machine base 10. This bore is also provided within a slotted casing 39 50 which may be clamped by means of a binding screw 40. The wheel adjusting unit supported by the quill 35 may be readily removed by unclamping the screw 37 and withdrawing the entire unit including the bevel gear 32 out of the 55

bore 36 and placing the quill 35 within the bore 38 so that the machine may be set up so that the wheels may be adjusted vertically from either end of the machine base, depending upon 5 the particular set-up of the machine.

Transversely movable carriage

The base 10 also supports a transversely movable carriage 45 which is supported on a transverse dovetailed slideway 46 on the base 10. The carriage 45 is provided with correspondingly shaped dovetailed ways 47 which mate with the dovetailed way 46 on the base 10. An adjustable gib 48 is provided as one part of the dovetailed 15 way on the carriage 45 and serves to adjust the dovetailed ways between the base 10 and the carriage 45. The carriage 45 may be moved transversely on the base by means of a manually operable hand wheel 49 which is mounted on the 20 outer end of a feed screw 50. The feed screw 50 is rotatably supported in bearings 51 and 52 which depend from the under side of the carriage 45. The screw 50 engages a nut 53 which is fixed to the base 10 so that any rotary motion 25 of the screw 50 will cause a transverse movement of the slide 45 relative to the base 10. To facilitate adjustment of the transverse slide so that it may be adjusted from either the front or rear of the machine, a manually operable hand wheel 30 54 is provided on the rear end of the feed screw 50.

The transversely movable carriage 45 is provided with a flat way 58 and a V-way 59 which serve to support a longitudinally movable work 35 supporting table 60. The table 60 is provided with a pair of mating ways comprising a flat way 61 and a V-way 62.

The table 60 supports a swivel table 63 which in turn serves as a support for rotatable work 40 supporting members including a headstock 64 having a headstock center 65 and a footstock 66 having a footstock center 67 which serve to rotatably support a fluted cutter or other work 45 piece or tool to be ground in operative relation with the grinding wheels 16 and 17.

The longitudinally movable work table 60 may be traversed or reciprocated longitudinally relative to the carriage 45 and the base 10 either manually or by a power operated mechanism, 50 as will be hereinafter described. The power operated mechanism preferably comprises a fluid pressure system comprising a cylinder 70 which is provided with supporting brackets 71 and 72 which are supported on the lugs 73 and 74 which 55 are formed integral with the carriage 45. A piston 75 is slidably mounted within the cylinder 70 and is connected with a double end piston rod 76 which extends through cylinder heads 77 and 78, respectively. The piston rod 76 is provided 60 at its opposite ends with nuts 79 and 80, respectively, which are in turn connected with depending brackets 81 and 82 depending from the under side of the table 60.

The brackets 81 and 82 are preferably detachably connected to the piston rod 76 by means of vertical slides 83 and 84 which in a downward position engage the rear surface of the nuts 79 and 80 so that when fluid under pressure is admitted to either a cylinder chamber 85 or a cylinder chamber 86, to move the piston 75 relative to the cylinder 70, a corresponding movement will be transmitted to the table 60. If desired, the fluid pressure piston and cylinder may be readily disconnected from the table 60 by raising 75 the slides 83 and 84 so that the slides 83 and 84

together with the brackets 81 and 82 will slide over the nuts 79 and 80 and permit table movement independent of the fluid pressure piston.

A fluid pressure system is provided to convey fluid under pressure to the cylinder 70 to cause a longitudinal movement of the piston 75 so as to traverse or reciprocate the work supporting table 60. This system may comprise a reservoir or sump 90 which is preferably located within the base 10. A fluid pump 91 conveys fluid from the reservoir through a pipe 92 and forces fluid through a pipe 93 to a reversing valve 95. The reversing valve 95 is preferably of a piston type comprising a valve stem 96 having formed thereon integral valve pistons 97, 98, 99, 100 and 101. Fluid under pressure from a pipe or passage 94 passes through a pipe or passage 102 into a valve chamber 103 between the valve pistons 98 and 99 and in the position shown in Fig. 4 passes out through a pipe or passage 104 into a passage 105 within the cylinder casing 70 and into the cylinder chamber 85 to cause the piston 75 to move toward the right, as viewed in Fig. 4.

During the movement of the piston 75 toward the right, as above described, fluid exhausts from the cylinder chamber 86 through a passage 107 within the cylinder casing 70 and through a pipe or passage 108 into a valve chamber 109 between the valve pistons 99 and 100 and out through a pipe or passage 110.

In order to control the speed of movement of the table 60, a control valve 112 is provided in the system and is preferably located in the exhaust side of the system so as to control the exhaust of fluid from the cylinder chamber 86 or 85. The control valve 112 is preferably of a piston type and comprises a valve stem 113 having formed integrally thereon valve pistons 114, 115 and 116. The pipe or passage 110 conveys fluid into a V-shaped chamber 117 which is cut in the periphery of the valve piston 115, which passes out through a port 118 and through a passage 119 and is returned to the reservoir 90. As indicated in Fig. 4, fluid returns through a pipe 120 to the reservoir 90. In actual construction, however, as shown in Fig. 6 of the drawings, the passage 119 in the valve 112 exhausts fluid from the system into a chamber 121 formed in the transversely movable carriage 45 and passes from the chamber 121 through a short tube 122 (Fig. 5) into the base 10, the lower portion of which is formed as a reservoir 90. The tube 122 passes through an elongated slot 123 in the base 10. The slot 123 is of sufficient length to allow the desired transverse movement of the carriage 45.

In order to control the speed of movement of the table 60, the V-shaped chamber within the valve piston 115 may be rotated to vary the aperture of the port 118. To facilitate a rotary adjustment of the valve member, and particularly the V-port 117, a control knob 125 is fixedly mounted on the outer end of the valve stem 113.

It is desirable to be able to quickly slow down the table 60 to a predetermined slow uniform speed for truing and then to rapidly return the table to the desired grinding speed. This is preferably accomplished by providing markings or graduations on the dial face of the knob 125 which may be turned to coincide with an index marker 126 which is carried by a bushing 127. In order to hold the valve in adjusted position, the valve stem 113 is provided with a serrated portion 124 which is engaged by a spring-pressed pawl 128 supported in the valve casing of the 75

vale 112. In order to provide a quick adjustment of the speed to produce a slow truing speed, the dial 125 is provided with a rearwardly projecting lug 129 which is arranged in the path of 5 an adjustable stop screw 130 carried by the bushing 127. The screw 130 is adjusted so as to locate the V-port 117 in the valve 115 in the desired relationship with the port 118 to produce the desired slow table speed for truing of the 10 grinding wheels. The knob 125 may then be rotated to open the V-port 117 and allow the table to travel at the desired grinding speed. At any time during operation of the machine, the knob 125 may be quickly and readily turned until 15 the lug 129 engages the end of the stop screw 130 to produce a slow uniform truing speed of the table. The screw 130 is preferably provided with a lock nut 131 which serves to lock the screw in its predetermined adjusted position.

20 When it is desired to stop the fluid pressure traverse of the work table 60, the valve stem 113 may be moved toward the left, as viewed in Fig. 4, which serves to move the V-port 117 in the piston 115 into the position 117a, thereby closing 25 the passage or pipe 110 and cutting off the exhaust of fluid from the cylinder chamber 86. At the same time, the movement of the valve piston serves to move a valve chamber 185 between the valve pistons 115 and 116 toward the 30 left, as viewed in Fig. 4, so that fluid exhausting from the cylinder chamber 86 may pass through 35 the valve chamber 109 in the reversing valve 95 and through a pipe or passage 136, through the valve chamber 185, and through a pipe or passage 137, which is connected with the valve chamber 103. The valve chamber 103 is connected by the pipe 104 and the passage 105 with the cylinder chamber 85, thereby allowing fluid within the system to readily by-pass from the cylinder chamber 86 to the other cylinder chamber 85 when the control valve is in a stopped position. This by-pass from one cylinder chamber to the other permits the table to be readily traversed manually without the necessity of over- 40 coming pressure of fluid within the fluid pressure system.

In order to readily control the in-and-out movement of the valve, a control lever 140 is pivotally mounted on a stud 141 supported on 50 a bracket 142. The lever 140 is provided with an enlarged portion 143 having an aperture 144 which surrounds the bushing 121. The lever 140 is provided with a pair of diametrically opposed screws 145 and 146, the inner ends of which ride 55 in slots 147 and 148 cut in the periphery of the bushing 127 so that when the lever 140 is moved from the table operating position, as shown in full lines in Fig. 6, into a broken line position 140a to close the valve, it serves to move the 60 valve stem 113 toward the right, as viewed in Fig. 6, to close the V-port 117 and open the by-pass between the opposite ends of the cylinder. The bushing 127 is provided with a depending pin 149 which engages a slot 150 in the lever 140 and serves to hold the bushing 127 against rotation.

To facilitate reversing the direction of movement of the table either automatically or manually, a reversing lever 155 is provided. This lever 70 is provided with a slot 156 at its lower end and is arranged to fit upon a transversely extending rock shaft 157 and may be clamped in adjusted position thereon by means of a clamping screw 158. The shaft 157 is supported in bearings 159 75 in the transversely movable carriage 45. A de-

pending arm 160 is keyed to the shaft 157 and held in position thereon by a nut 161. The lever 160 has a projecting boss 162 which supports a lever 163, the upper end of which is provided with a pin 164. The pin 164 engages a groove 5 165 in a spool shaped member 166 mounted on the end of the reversing valve stem 96 so that when the lever 163 is rocked on the boss 162, it will transmit an endwise movement to the valve stem 96 to reverse the valve and thereby change 10 the direction of movement of the fluid under pressure within the system. The lower end of the lever 160 is provided with a pair of outwardly extending bosses 167 and 168, each of which supports a spring-pressed plunger 169 and 170, re- 15 spectively. The plungers 169 and 170 engage opposite sides of a circular end portion 171 of the lever 163 and serve as a load-and-fire mechanism to aid in throwing the reversing valve into a central position. Each of the plungers is backed by 20 a spring 172 and 173, respectively, the tension of which may be adjusted by means of adjusting screws 174 and 175.

In order to automatically reverse the movement of the table 60, a pair of adjustable table 25 dogs 176 and 177 are adjustably supported in a T-slot in the front edge of the table 60. When the table is reciprocated longitudinally, the movement continues until the dog 176 contacts the lever 155. The table 60 is moving toward the 30 right, as viewed in Fig. 5. This movement continues until the table dog 176 strikes a projecting arm 179 of the reversing lever 155 and rocks the lever in a clockwise direction. This movement also serves to rock the lever 160 in a clockwise direction, as viewed in Fig. 5, serving to de- 35 press the plunger 170 and compress the spring 173 until there is sufficient energy in the spring to shift the lever 163 so as to move the valve stem 96 toward the right, as viewed in Figs. 4 and 5. 40

The movement of the valve stem 96 toward the right continues under the influence of the lever 155 until the valve piston 98 moves toward the right a sufficient distance to allow fluid under pressure to pass through a port 185 and into a 45 valve chamber 186 between the valve pistons 97 and 98. Due to the fact that the effective cross sectional area of the piston 98 is greater than the effective cross sectional area of the piston 97, the fluid under pressure entering the chamber 186 50 serves to complete the movement of the valve stem 96 toward the right, as viewed in Fig. 4, shifting the valve into its extreme right-hand position so that fluid under pressure passing through the pipe or passage 94 passes through a 55 pipe or passage 187 into the valve chamber 109 between the valve pistons 99 and 100 and out through the pipe or passage 108 into cylinder chamber 86 to cause the piston 75 and the table 60 to move toward the left, as viewed in Fig. 4. When 60 the table reaches the end of its stroke toward the left, the reversal is automatically made in a manner similar to that described above. The dog 177 serves to rock the reverse lever 155 to move the valve stem 96 until the valve piston 100 uncovers 65 a valve port 188 to admit fluid under pressure into a valve chamber 189 between valve pistons 100 and 101 and due to the differential piston areas between the pistons 100 and 101 causes the reversing valve to reverse into the position shown 70 in Fig. 4 under the influence of fluid under pressure.

If it is desired to traverse the table beyond the normal reciprocatory stroke thereof, it is desirable to provide means to render either the reverse 75

lever or the dogs ineffective. In the preferred construction, as illustrated in the drawings, the reverse lever 155 is made in two parts. The upper portion 155 slides on a cylindrical lower portion 190 and is normally held in an upward position by means of a spring 191. If it is desired to pass beyond either the table dog 176 or 177, the knob 192 of the reversing lever 155 may be pushed downwardly against the tension of the spring 191 to lower the projecting arm 179 below the path of the dogs 176 or 177. A pin 193 in the lever 155 engages an elongated slot 194 in the lower portion 190 and serves to maintain the arm 179 in the proper position. The elongated slot 194 is required when the knob 192 of the reverse lever 155 is pushed downwardly so that the arm 179 will be below the dogs 176 and 177.

The reversing lever 155 may be either actuated automatically by means of the table dogs or manually by means of the knob 192. In certain types of tool grinding, it is desirable for the operator to stand at the rear of the machine in order to control the movement of the tool relative to the grinding wheel and to observe the grinding operation as it proceeds. In this case, it is desirable to provide an auxiliary reversing lever 195 which is clamped by means of a screw 196 on the rear end of the shaft 157 so that the reversing valve may be manually operated from the rear of the machine.

A manually operable traversing mechanism is provided for manually reciprocating or traversing the table 60. This mechanism, as illustrated, is preferably of a two feed type, such as that disclosed in the prior patent to Norton and Turner No. 1,299,765 dated April 8, 1919. The table 60 is provided with a depending rack bar 200 which meshes with a gear 201 which is slidably keyed to a rotatable shaft 202. The shaft 202 is supported in bearings 203 and 204 in the carriage 45. A large gear 205 is keyed to the outer end of the shaft 202. A manually operable hand traverse wheel 206 is rotatably mounted on an outwardly extending shaft 207. The hand wheel 206 carries a rotatable shaft 208 having formed integrally thereon a gear 209 which meshes with the internal gear 210, which is mounted on the hub of a gear 211 which is rotatably mounted on the shaft 207. Gear 211 meshes with the gear 205. The shaft 208 rotatably supports a gear 212 which in turn meshes with a non-rotatable internal gear 213 which is fixed relative to the carriage 45. In the position of the parts illustrated, when the hand wheel 206 is rotated to traverse the table, this rotary motion is transmitted through the teeth of the gear 209 to rotate the gear 210 at the same speed at which the hand wheel is rotated to transmit a rotary motion through the gears 211 and 205 to rotate the shaft 202 and the gear 201 to cause a longitudinal traversing or reciprocatory motion to the table 60.

The outer face of the gear 212 is provided with clutch teeth 214 which are arranged to be engaged by clutch teeth 215 on a movable clutch member 216. The clutch member 216 is slidably keyed to the shaft 208 and is arranged to be moved into or out of operative engagement with the clutch teeth 214 by means of a control knob 217. A pair of diametrically opposed spring-pressed plungers carried by the member 218 engage grooves in the outer periphery of the sleeve formed integral with the clutch member 216 and serve to hold the clutch member 216 either out of operative engagement, as shown in Fig. 8, or into operative engagement when the knob 217 is

pushed toward the right, as viewed in Fig. 8. The pressure of the pair of spring-pressed plungers carried by the member 218 may be adjusted by the pair of screws 219 and check nuts. If a slow hand traversing movement of the table is desired, the knob 217 is pushed toward the right, as viewed in Fig. 8, so that the teeth 215 of the clutch member 216 are thrown into engagement with the clutch teeth 214 on the gear 212. In this position of the parts, movement of the hand wheel 206 revolves the gears 209 and 212 about the axis of the shaft 208, but the pinion 212 meshing with a fixed internal gear 213 is thereby forced to rotate, turning the gear 209 with it, which in turn rotates the internal gear 210 and causes a differential movement between the parts, this movement being transmitted to the gears 211 and 205 to rotate the shaft 202 at a slow feed, which motion is transmitted to gear 201 to the rack 200. By this mechanism, the table 60 is moved slowly and thereby is obtained a fine position or is produced manually a sufficiently uniform rate of motion for such accuracy of work as is required in truing a grinding wheel. Full details of this mechanism have not been illustrated in the present case, since this feature in itself is not considered part of the present invention. For complete details of the construction of this hand traverse mechanism, reference may be had to the above-mentioned Patent No. 30 1,299,765.

It is desirable to provide a suitable interconnection between the hydraulically operated table reciprocating mechanism and the manually operable traverse mechanism so that when the table 60 is reciprocated by means of the fluid pressure piston and cylinder, the manually operable traverse mechanism will be rendered inoperative so that the hand wheel remains stationary during the power reciprocation of the table 60. This is preferably accomplished by an electrically operated mechanism. The gear 201 is provided with an extending hub 225 which is provided with a groove 226. The groove 226 is engaged by a projection 227 on a rock arm 228 pivotally mounted on a stud 229. In the full line position of the parts, as illustrated in Fig. 4, the table is under fluid pressure control and the rock arm 228 is swung to the dot and dash position so as to slide the gear 201 out of mesh with the rack 200 against the tension of a spring 230. The gear 201 is thrown into the position illustrated in Figs. 4 and 8 by an electrically operated mechanism including a solenoid 231, the core of which is connected by a link 232 with the rock arm 228. A limit switch 233 is in a closed position, as indicated in Fig. 4, and serves to energize the solenoid 231 so as to throw the gear 201 out of mesh with the rack bar 200. When it is desired to stop the fluid pressure movement of the table 60, the control lever 140 is moved into a broken line position 140a, as indicated in Fig. 6, which serves to move the valve stem 113 toward the right, as viewed in Fig. 6, so as to move the V-chamber 117 so as to close the pipe or passage 110 and thereby stop the fluid pressure movement of the table 60. This movement also serves to move the fluid pressure chamber 135 located between the valve pistons 115 and 116 into alignment with the pipes or passages 136 and 137 to allow a by-passing of fluid between the cylinder chambers 85 and 86 on opposite sides of the piston 75. During this movement of the control valve 112, a projecting pin 234 on the valve stem 113 engages a roller 235 which is mounted on a rock arm 236 of the limit 75

switch 233. The pin 234 serves to rock the arm and the roller into the dotted line position 235a which serves to open the circuit of the electrical contact portion of the rock arm 236 against the 5 tension of the spring 237, thereby deenergizing the solenoid 231 and allowing the released tension of the spring 230 to throw the gear 201 into mesh with the rack bar 200 so that the table may be traversed manually by rotating the manually 10 operable traverse wheel 201. Similarly, when it is desired to start the table movement under the influence of fluid under pressure, the control valve lever is moved from the position 140a into the full line position 140, as indicated in Fig. 6, which 15 serves to move the valve stem 113 toward the right, as viewed in Fig. 4. This movement cuts off the by-pass of fluid between the pipes 136 and 137 and moves the V-chamber 117 into alignment with the pipe 110 to allow fluid pressure to 20 exhaust from the system. At the same time, the valve stem 113 is moved toward the right, Fig. 4. The pin 234 on the valve stem 113 moves into the position as illustrated in Figs. 4 and 6 out of contact with the roller 235, allowing the rock arm 25 236 to assume the full line position of the parts, as illustrated in Fig. 4, thereby closing the circuit to energize the solenoid 231. The energizing of the solenoid 231 serves to move the link 232 and rock the arm 228 in a clockwise direction (Fig. 4) 30 to move the gear 201 out of mesh with the rack bar 200 and thereby to render the manual traverse mechanism inoperative during the table traverse movement under fluid pressure.

In the grinding of straight fluted and spiral tools, such as reamers or milling cutters, it is necessary for the cutter to be mounted on centers 35 65 and 67 and the cutting edge to be ground located by means of a tooth rest (not shown). The tooth rest serves to maintain either the straight 40 cutting edge or the spiral edge in proper operating position relative to the grinding wheels 16 or 17. It is necessary in such an operation to cause one complete reciprocation of the table, that is for the table to grind across the cutting edge 45 once in each direction and to then stop so as to permit indexing of the cutter to bring the next tooth into operative relation with the wheel. In such an operation, the operator's attention must be directed to maintaining the tool in operative 50 contact with the tooth rest and it is, therefore, desirable to provide a suitable means for causing one complete reciprocation of the table and then stopping the same automatically without attention 55 on the part of the operator. This is preferably accomplished by providing a third adjustable table dog 240 which is reversible and interchangeable so that it may be located either in the full line position, Fig. 5, or in the broken line position 240a at the other end of the table. The 60 dog 240 is arranged to engage a fixed stop 241 or 242 at the end of the table stroke. The dog 240, when used, is preferably located on the other side of the dog 176 in a definite relationship with the reversing dogs 176 or 177, depending upon 65 which of the fixed stops 241 and 242 is used, so that the reversing dog 176 will not contact the projection 179 of the reversing lever 155. The dog 177 will contact the projection 179 and reverse the table 60 and when the dog 240 contacts the stop 241, the stroke is complete. The dog 240 engages the fixed stop 241 or 242 so as to stop the longitudinal movement of the table 70 60 and to hold the table stationary against the fluid pressure mechanism, tending to traverse the table. In case the pressure builds up within the 75

system beyond a desired point, a release valve 243 in the pipe line 93 opens and allows the excess fluid under pressure to exhaust through a pipe 244 into the reservoir 90. With this arrangement of the parts, the machine may be set up to grind a 5 fluted cutter, starting either at the headstock or footstock end of the machine, and the lever 155 is thrown manually to start the table moving in one direction while the operator holds the fluted cutter in operative relation with the tooth rest. The 10 table continues its stroke in one direction and the dog 176 or 177 engaging the projection 179 of the reverse lever 155 causes a reverse movement of the table 60, passing the cutting edge of the cutter again across the face of the wheel until the stop 15 dog 240 or 240a engages the fixed stop 241 or 242 so as to stop the table movement after one complete reciprocation so as to permit indexing of the cutter to move the next edge to be ground into operative relation with the wheel and tool threads. 20

It will thus be seen that there has been provided by this invention apparatus in which the various objects hereinabove set forth together with many thoroughly practical advantages are successfully achieved. As many possible embodiments may be 25 made of the above invention and as many changes might be made in the embodiment above set forth, it is to be understood that all matter hereinbefore set forth or shown in the accompanying drawings is to be interpreted as illustrative and not in a 30 limiting sense.

I claim:—

1. A grinding machine comprising a rotatable grinding wheel, a rotatable work support, a longitudinally movable table for said support, means to move the grinding wheel and work support transversely relative to each other, manual means to traverse said table longitudinally, a fluid pressure system including a piston and cylinder operatively connected to reciprocate the table longitudinally, means including a reversing valve to change the direction of movement of the table, a control valve which serves in one position to control the speed of movement of the table and in a second position to permit a by-passing of 45 fluid from one end of the cylinder to the other, and means actuated by the movement of the control valve to render the manual traverse mechanism inoperative.

2. A grinding machine comprising a rotatable grinding wheel, a rotatable work support, a longitudinally movable table for said support, means to move the grinding wheel and work support transversely relative to each other, manual means to traverse said table longitudinally, a fluid pressure system including a piston and cylinder to reciprocate the table longitudinally, means including a reversing valve to change the direction of movement of the table, a control valve which serves in one position to control the speed of 60 movement of the table and in a second position to permit a by-passing of fluid from one end of the cylinder to the other, and means actuated in timed relation with the movement of said control valve to render the manual traversing mechanism operative.

3. A grinding machine comprising a rotatable grinding wheel, a rotatable work support, a longitudinally movable table for said support, means to move the grinding wheel and work support transversely relative to each other, manual means to traverse said table longitudinally, a fluid pressure system including a piston and cylinder to reciprocate the table longitudinally, means including a reversing valve to change the direction 70 75 75

- of movement of the table, a control valve which serves in one position to control the speed of movement of the table and in a second position to permit a by-passing of fluid from one end of the cylinder to the other, and electrically operated means actuated by movement of said control valve to render the manual traversing mechanism inoperative when the control valve is moved to reciprocate the table by fluid pressure.
5. A grinding machine comprising a rotatable grinding wheel, a rotatable work support, a longitudinally movable table for said support, means to move the grinding wheel and work support transversely relative to each other, manual means to traverse said table longitudinally, a fluid pressure system including a piston and cylinder to reciprocate said table longitudinally, means including a reversing valve to change the direction of movement of the table, a control valve in said system which is arranged to stop and start the table reciprocation and to control the speed of movement of the table, electrically operated means including a limit switch which is actuated by movement of said control valve, and means including a solenoid controlled by said switch and arranged to render the manual traverse mechanism inoperative during the fluid pressure reciprocation of the table.
6. A grinding machine comprising a rotatable grinding wheel, a rotatable work support, a longitudinally movable table for said support, means to move the grinding wheel and work support transversely relative to each other, manual means to traverse said table longitudinally, a fluid pressure system including a piston and cylinder to reciprocate said table longitudinally, means including a reversing valve to change the direction of movement of the table, a control valve in said system which is arranged to stop and start the table reciprocation and to control the speed of movement of the table, electrically operated means including a limit switch which is closed by movement of said valve into a table reciprocating position, a solenoid controlled by said switch, and means actuated by said solenoid to render the manual traverse mechanism inoperative during the fluid pressure reciprocation of the table.
7. A grinding machine comprising a rotatable grinding wheel, a rotatable work support, a longitudinally movable table for said support, means to move the grinding wheel and work support transversely relative to each other, manual means including a rack and gear to traverse said table longitudinally, a fluid pressure system including a piston and cylinder to reciprocate said table longitudinally, means including a reversing valve to change the direction of movement of the table, a control valve in said system which is arranged to stop and start the table reciprocation and to control the speed of movement of the table, means to hold said gear in engagement with said rack, electrically operated means including a solenoid to disengage the gear from the rack, and means including an electric switch which is actuated by movement of said control valve which serves to render the manual traverse mechanism inoperative during the fluid pressure reciprocation of the table.
8. A grinding machine comprising a rotatable grinding wheel, a rotatable work support, a longitudinally movable table for said support, means to move the grinding wheel and work support transversely relative to each other, manual means to traverse said table longitudinally, a fluid pressure mechanism including a piston and cylinder which are operatively connected to reciprocate said table, a reversing valve therefor, a control valve which is arranged to stop and start said table and to throttle the exhaust of fluid from said cylinder to control the table speed, a manually operable lever on the front of said machine base to operate said reversing valve, adjustable dogs on said table to automatically actuate said lever so as to reciprocate said table through a predetermined stroke, and manually operable lever on the rear of the machine base which is operatively connected to manually actuate said reversing valve.
9. A grinding machine comprising a rotatable grinding wheel, a rotatable work support, a longitudinally movable table for said support, means to move the grinding wheel and work support transversely relative to each other, a fluid pressure system including a piston and cylinder to reciprocate said table, a reversing valve therefor, a control valve to stop and start said table and to throttle the exhaust of fluid from said cylinder to control the table speed, a manually operable lever to actuate said reverse valve, adjustable dogs on said table to actuate said lever to automatically reciprocate said table, and means including an adjustable dog on said table and a fixed stop on said base to stop the table movement after one complete reciprocation thereof.
10. A grinding machine comprising a rotatable grinding wheel, a rotatable work support, a longitudinally movable table for said support, means to move the grinding wheel and work support transversely relative to each other, a fluid pressure system including a piston and cylinder to reciprocate said table, a reversing valve therefor, a control valve to stop and start said table and to throttle the exhaust of fluid from said cylinder to control the table speed, a manually operable lever to actuate said reverse valve, adjustable dogs on said table to actuate said lever to automatically reciprocate said table, and means including an adjustable dog on the table and a fixed stop cooperating therewith to stop the table at either end of its stroke after one complete reciprocation.

CHARLES H. AMIDON.
